UNITED STATES PATENT OFFICE.

RENÉ BIENVENÜE AND JOSEPH BIENVENÜE, OF PARIS, FRANCE.

CURRENT COLLECTOR FOR RAILWAY VEHICLES.

Application filed April 15, 1920. Serial No. 374,098.

To all whom it may concern:

Be it known that we, RENÉ BIENVENÜE and JOSEPH BIENVENÜE, both citizens of the French Republic, and both residing in the 5 city of Paris, France, have invented new and useful Improvements in a Current Collector for Railway Vehicles, of which the following is the specification.

This invention has for its object a current 10 collector allowing a railway vehicle to establish an electric connection between this vehicle and a contact device arranged on the railway track.

In the accompanying diagrammatic drawings, given by way of example only,

Figure 1 is a front view of a wheel provided with a rotary shoe forming the subject-matter of this invention.

Figure 2 is an edge view of the structure 20 seen in Fig. 1, some of the parts being in section.

Figure 3 is a partial detail section of the wheel and rolling shoe, showing the arrangement of the insulation and a method 25 of securing in position the contact ring.

The rotary shoe, which may be mounted either on the front wheels of a locomotive, or on the wheels of a tender or wagon, is constituted by a ring p made of bronze or any 30 other metal, secured on the wheel i^1 and electrically insulated from the latter by a washer p^1 made of fibre or any other suitable insulating material, as shown in Fig. 3. This ring is mounted on a carrying wheel 35 of the vehicle by screws p^3 passing through sockets p^2 made of insulating material.

The ring p is electrically connected to the interior of the vehicle by any means, for instance through the medium of a roller p^5 40 (Figs. 1 and 2) running in a groove p^4 provided in the periphery of the ring p and held in this groove by a blade p^6 acting as a spring and mounted on an armature p^7 electrically insulated from the frame of the locomotive, tender or wagon.

The conductor g^2 is connected, at one of its ends, to one of the poles of any source of electricity arranged within the vehicles and to the apparatuses inserted in the circuit of this source of electricity, and at the end, is connected to the frame of the vehicle.

The conductor g is connected, at one of its ends, to the other pole of the source of electricity and, at the other end, to a terminal 55 p^8 (Fig. 1) carried by the blade p^6 .

The contact device arranged on the railway track is constituted by a flexible blade capable of coming in contact, in any manner whatever, with the ring p . It is constituted, for instance as shown in Fig. 2, by a metallic flexible blade q^1 mounted on a wooden member q . This flexible blade q^1 and the wooden member q are secured on the sleepers of the track. It extends above the level of the rail, which it must not touch, and is arranged at such an height that it can be engaged by the ring p when the latter passes over the said blade.

To the blade q^1 is secured a connection q^2 connected to the row of rails on which runs 70 the wheel i^1 provided with the insulated ring p .

The device operates as follows:

When the vehicle runs on the track the ring p comes in contact with the flexible 75 blade q^1 , the circuit is closed and the current, coming from the source of electricity, passes through the connection g , terminal p^8 , blade p^6 , roller p^5 , ring p , blade q^1 , connection q^2 , the rail, wheel i^1 , axle and bearing of the wheel, frame of the vehicle, connection g^2 , and the apparatus inserted in the circuit to the other pole of the source 80 of electricity.

What we claim as our invention and desire to secure by Letters Patent is:

1. A current collector for railway vehicles, comprising: a rotary shoe secured on a carrying wheel of any vehicle and constituted by a metal ring mounted on the side of the wheel, this ring being insulated from the wheel by a sheet of insulating material and attached to the wheel by insulated fastening means—a device adapted to transmit within the vehicle the current collected by the ring, 95 this device being constituted by a roller running in a groove provided on the periphery of the ring and secured by a spring to the frame of the vehicle by means of an insulated securing device.

2. A current collector for railway vehicles, comprising: a rotary shoe secured on a carrying wheel of any vehicle and constituted by a metal ring mounted on the side of the wheel, this ring being insulated from the wheel by a sheet of insulating material and secured to the wheel by insulated fastening means,—a device adapted to transmit within the vehicle the current collected by the ring, this device being constituted 105 110

- by a roller running in a groove provided in the periphery of the wheel and secured by a spring to the frame of the vehicle by means of an insulated fastening means, a device, connected to the rail by a connection, arranged on the side of the track and adapted to enter in engagement with the rotary shoe secured on a carrying wheel of the vehicle.
- 10 3. A current collector for railway vehicles, comprising: a rotary shoe secured on a carrying wheel of any vehicle constituted by a metal ring mounted on the side of the wheel, this ring being insulated from the 15 the wheel by a sheet of insulating material and secured to the wheel by insulated fastening means,—a device adapted to transmit within the vehicle the current collected by the ring, this device being constituted by 20 a roller running in a groove provided on the
- periphery of the ring and secured by a spring to the frame of the vehicle by means on an insulated fastening means,—a device, connected to the rail by a connection, arranged on the side of the track and adapted 25 to enter in engagement with the rotary shoe secured on a carrying wheel of the vehicle, this device being constituted by a flexible metal blade mounted on a wooden member and coming in contact in any way whatever, 30 either at the periphery or at the side, with the rotary shoe.

In testimony whereof we have signed our names to this specification in the presence of two subscribing witnesses.

RENÉ BIENVENÜE.

JOSEPH BIENVENÜE.
